WASHER LOADING DEVICE

Filed Jan. 12, 1927

UNITED STATES PATENT OFFICE

SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

WASHER-LOADING DEVICE

Application filed January 12, 1927. Serial No. 160,660.

This invention relates to placing perforated articles upon pins and is herein illustrated as embodied in a device for placing washers upon the pins of a rubber heel mold.

5 Rubber heels commonly have embedded in them a series of small washers, the holes through which register with the nail holes in the heel. These washers are commonly dish-shaped, the open sides thereof being 10 faced toward the bottom of the heels so that the nails, when driven, will be guided into the nail holes. The molds in which rubber heels are molded and vulcanized comprise base plates having a plurality of upstanding 15 pins which form the holes in the finished heels. Upon these pins, the washers must be placed before the so-called "biscuits" of rubber are put into the molds; and the device of the present invention is adapted to perform 20 this washer-placing operation.

The illustrated device is of the type which is operated by relative traverse between it and the mold, the present invention being directed more particularly to the provision of 25 novel means for displacing a washer from the stack and for holding it in position to be threaded upon a mold pin.

According to one feature of the invention the stack is supported by a plurality of 30 members, one of which is capable of yielding; and the lowermost washer of the stack, after it has been displaced, is held by this member until it is engaged by and threaded upon the mold pin. In the illustrated construction, the under side of the lowermost washer is supported at its forward portion 35 by a rigid member and at its rear portion by a yielding member; and the feed slide, referred to above, pushes the lowermost washer out of its position in the stack into a position where it is supported by the yielding member preparatory to being threaded upon the pin.

40 With a construction of the kind outlined above, each washer is moved out of its stacked position prior to being engaged by a mold pin and is held in such position that the pin engages it properly.

50 These and other features of the invention

including certain details of construction and combinations of parts will be described as embodied in an illustrative machine and pointed out in the appended claims.

Referring to the accompanying drawings, 55 Figure 1 is a perspective of a device in which the present invention is embodied.

Figures 2, 3, 4 and 5 are fragmentary views in vertical longitudinal section showing different positions occupied successively 60 by parts of the device. In these figures, certain parts of the device have been omitted to simplify the showing.

Figure 6 is a perspective of the feed slide and its operating mechanism, and 65

Figure 7 is a perspective of the under side of the device showing more particularly the parts which engage the mold pins.

The device comprises an elongated flat shoe 15 having its forward end bent up at 17, and a handle 19 fastened to the upper part of the upright arm of an angle iron 21, the horizontal arm of which is fastened to the shoe 15 by screws 23. The device is adapted to be moved forward and back over the rows of 20 mold pins of a rubber heel mold and, during the forward strokes, to deposit a washer upon each pin over which it passes. The washers 100, herein shown as of the dished type, are stacked, open sides down, in nested 25 relation in a magazine in the form of a tube 25, the lower end of which is fast to and extends through a block 27, which extends down through an opening in the shoe 15. This block is forked at its forward end and has at 30 the outer ends of the arms of the fork upstanding lugs having aligned bores through which pass loosely aligned studs 29, 31 which are held in upright lugs formed at the rear 35 end of a bracket 33, said bracket being fastened to the shoe 15 by screws 35. The block 27 and the tube 25 may thus be adjusted about the common axis of the studs 29, 31. The block and tube are held yieldingly in adjusted angular position by means of a tension 40 spring 37 and a stop screw 39, the latter being threaded through the upright arm of the angle iron 21. By adjusting the stop screw the angular position of the block 27 and tube 45 25 may be changed. It will be noted that, 45

with this construction, the block may rise and fall about the axis of the studs 29, 31.

The stack of washers is held from sliding down through the tube, when no washer is being delivered to a mold-pin, by engagement of certain parts of the device with two separated localities on the under face of the lowermost washer,—namely, a forward locality and a rearward locality as shown in Figures 2 and 5. The washer is really engaged in two localities at the forward end and two at the rearward end since, as will appear from Figures 3 and 4, a passageway longitudinally of the median line of the shoe 15 must be provided so that the mold pin 200 may engage the lowermost washer in a manner presently to be explained. The under side of the forward portion of the lowermost washer is engaged by two spaced flat surfaces, one of which is indicated at 41 (Fig. 2), said surfaces being formed on a part of the block 27 to which the tube 25 is fast. The under side of the rear portion of the lowermost washer is engaged at two spaced localities by thin flanges, one of which is shown at 43. These flanges project inwardly (that is from the sides of the shoe 15 toward the longitudinal median line thereof) from the inner sides of substantially horizontally extending extensions 45 formed at the lower ends of thin arms 145. These arms have forward extensions 245 above the shoe 15 which are pivoted respectively about the studs 29, 31 and are urged upwardly at all times by compression springs 47. Referring still to Figures 2 and 5 as well as to Figure 1, it will be seen that the stack of washers is held securely in the tube but that, if force were applied to the forward edge of the lowermost washer to push it rearwardly, said washer could be pushed out of the tube over the flanges 43 which would yield to permit such passage of said washer.

In the illustrated construction a slide operated by engagement with a mold pin pushes the lowermost washer into the approximate position shown in Figure 3; and subsequently the mold pin engages the hole in the washer, as shown in Figure 4, and removes the washer entirely from the device (Fig. 5). This slide 49 has on its opposite sides ribs 51 (Fig. 6), which are received in grooves, one of which is shown at 53 (Fig. 3), formed in the inner faces of the arms of the fork at the forward end 55 of the block 27; and extending from its rearward end is a feed member, in the form of a thin plate 149 having a notched extremity, as shown in Figure 6, to engage the periphery of a washer. In order to cause the slide 49 to be operated at the proper time, an actuator 55, which normally lies in position to be engaged by a mold-pin, is connected with the slide in the following manner. This actuator is fast to the lower end of a small upright shaft 57 which is rotatable in the block

27, the upper end of said shaft being fast to one end of an arm 59, the other end of which is pivoted about a pin 61, carried at the outer end of a link 63. The end of the link 63 which is remote from the pin 61 is pivoted at 65 to the slide 49, and a tension spring 67 connects the pin with a screw 69 carried by the bracket 33 which is rigid with the shoe 15. The actuator 55 is in the form of an arm the outer end of which normally extends across and in front of the passageway between downwardly extending projections 127, 227 on the block 27. In front of the actuator 55 are two guides 71, 73, fast to the shoe 15, spaced apart and having converging faces, one of which is shown at 173 to guide a mold-pin to the actuator 55. The tension spring 67 tends at all times to hold the actuator 55 against the rear face of the guide 71, but permits the actuator to be swung to the rear about the axis of the small upright shaft 57 when said actuator is pushed against a mold-pin.

In the operation of the device, the tube 25 is first filled with stacked washers 100. The operator then seizes the handle 19 and pushes the device across a rubber heel mold, with the shoe 15 resting upon the tops of the mold-pins. Such mold-pins are commonly arranged in groups which are horse-shoe-shaped in outline, but the operator may select a series of pins which are approximately in line and so guide the device that the pins of the series are received successively between the converging faces of the guides 71, 73.

Figures 2, 3, 4 and 5 represent four positions of the device in its forward movement with respect to a stationary mold-pin 200. In Figure 2, the mold-pin is just in front of the converging guides 71, 73. As the device is moved forward into the position shown in Figure 3, the actuator 55 is swung to the rear by contact with the mold-pin, and the slide 49 is moved rearwardly on the block 27 through the small shaft 57 (Fig. 6), the arm 59 and the link 63. The pusher or feeder 149, being part of the slide, engages the forward edge of the lowermost washer and pushes the washer rearwardly over the supporting flanges 43 which yield through the springs 47 by which they are held up. The lowermost washer is not only thus displaced from the stack but is tilted somewhat, as shown in Figure 3, and held in position presently to be threaded upon the mold pin. As the device is moved farther forward into the position shown in Figure 4, the mold pin engages the hole in the washer; and, as the device continues its forward movement, the washer is threaded on the pin and dragged out of the stack as shown in Figure 5. Meantime, the pin has passed from beneath the tube 25, the pusher 149 has returned to its normal forward position, the

supporting flanges 43 have risen, the lowermost washer of the stack rests upon the surface 41 and the flanges 43 as in Figure 1, and the parts are in position to deposit said lowermost washer upon the next mold-pin 5 which is encountered.

Although the invention has been set forth as embodied in a particular device, it should be understood that the invention is not limited in the scope of its application to the particular device which has been shown and described.

In order to promote brevity as well as to point out a specific use of the device, the placing of washers upon the pins of a mold 15 has been described and will be deferred to generally throughout the claims, but without intending to exclude other articles which may be placed upon members other than the 20 pins of a heel mold.

This application has been filed concurrently with application Serial No. 160,239, filed Jan. 10, 1927, in which the generic claims 25 to subject-matter common to the construction shown in the two applications have been presented.

Having thus described my invention, what I claim as new and desire to secure by Letters Patent of the United States is:—

30 1. A device for placing washers upon the pins of a mold by relative traverse between the mold and the device, having in combination, a magazine for a stack of washers, a plurality of means for engaging the under 35 side of the lowermost washer to support the stack, one of said means being capable of yielding relatively to another of said means to enable the lowermost washer to be tilted, and means responsive to said relative traverse for moving said lowermost washer out 40 of stacked relation and into a tilted position while still engaged by said yielding means.

2. A device for placing washers upon the pins of a mold by relative traverse between 45 the mold and the device, having in combination, a magazine for a stack of washers, a plurality of means for engaging the under side of the lowermost washer to support the stack, one of said means being capable of yielding 50 relatively to another of said means to enable the lowermost washer to be tilted, and means operated by a mold pin during such traverse for moving said lowermost washer out of stacked relation and into a tilted position 55 while still engaged by said yielding means.

3. A device for placing washers upon the pins of a mold by relative traverse between 60 the mold and the device, having in combination, a shoe, a magazine for a stack of washers mounted upon the shoe and extending into an opening therethrough, a rigid member 65 arranged to engage the under side of the lowermost washer at one locality, a yielding member arranged to engage the under side of said washer at another locality, a feed slide

adapted to move the lowermost washer in the direction from the rigid member toward the yielding member, and an actuator for the feed slide located in position to be engaged and moved by a mold pin during said traverse 70 for operating the feed slide.

4. A device for placing washers upon the pins of a mold by relative traverse between the mold and the device, having in combination, a shoe, a magazine for a stack of washers mounted upon the shoe and extending into an opening therethrough, a rigid member 75 arranged to engage the under side of the lowermost washer at one locality, a yielding member arranged to engage the under side of said washer at another locality, a feed slide adapted to move the lowermost washer in the direction from the rigid member toward the yielding member, an actuator for the feed slide located in position to be engaged and moved by a mold pin during said traverse for 80 operating the feed slide, and means for holding the moved washer until it is engaged by the mold.

5. A device for placing washers upon the pins of a mold by relative traverse between the mold and the device having, in combination, a magazine for a stack of washers, means 90 for supporting the stack, and means independent of said supporting means and constructed and arranged by engagement with the side of a mold pin during such traverse 95 to move the lowermost washer of the stack out of stacked relation.

6. A device for placing washers upon the pins of a mold by relative traverse between the mold and the device having, in combination, a magazine for a stack of washers, means 100 for supporting the stack, and means constructed and arranged by engagement with the side of a mold pin during such traverse 105 to move the lowermost washer of the stack out of stacked relation.

In testimony whereof I have signed my name to this specification.

SIDNEY J. FINN.
